UNITED STATES PATENT OFFICE

ARTHUR L. CURRIER, OF ASHBURNHAM, MASSACHUSETTS, ASSIGNOR, BY MESNE ASSIGNMENTS, TO CORNELL BAG CORPORATION, A CORPORATION OF DELAWARE

MULTIWALLED BAG

Application filed June 9, 1928. Serial No. 284,236.

This invention relates to improvements in bags and more specifically to a novel form of folded end for bags.

The principal object of this invention, among others not enumerated, is that of providing an end construction for multi-wall bags which is strong, durable, efficient in operation and is cheaply, quickly and easily made.

10 The merits of the present invention will appear from the following disclosure of one embodiment of my invention, which is given merely by way of example, and the utility of the invention will be obvious from the advantages which are realized in the particular embodiment illustrated.

The following description will be more readily understood by referring to the accompanying drawing in which—

20 Figure 1 is a perspective view of a multi-wall bag having an end constructed in accordance with this invention.

Figure 2 is a perspective view of a bag having portions partially folded for forming an end in accordance with this invention, the view also showing how the tube is preferably first flattened before the end folds are made.

Figure 3 is a view similar to Figure 2 showing the first flap folded inwardly for the production of the end.

Figure 4 is a view similar to Figure 3 showing the second flap folded inwardly for the production of the finished end, and represents the step just prior to the finishing of the bag as shown in Figure 1.

Figure 5 is a perspective view showing the end of a bag of a modified form of my invention.

Figure 6 is a view similar to Figure 5 showing a modified form of notches for assisting in separating the individual plies.

Figure 7 is a perspective view of one end of a bag constructed in accordance with another modified form of my invention.

45 Figure 8 is a plan view of the construction shown in Figure 7 in its first folded position; and

50 Figures 9, 10 and 11 show the various steps of the subsequent folds producing the finished end shown in Figure 11.

When bags are made in accordance with the present disclosure, the multi-ply tubes from which the bags are made may have any number of plies and the bags may have both ends closed or only one end closed to form a bottom with its opposite end or top open.

55 It will be further understood that the invention is applicable for the production of bags having a completely closed end or ends, or bags provided with the well-known valve type of filling opening.

60 The multi-wall tube from which the bags are made in accordance with the present disclosure may be produced in any desirable manner, that is, they may be of a nested tube type or of a convolute type or any other suitable type.

65 By referring to the drawings, it will be noted that the invention is illustrated in connection with a bag 10 formed from a multi-wall tube 11 which has been previously flattened, as shown in the figures of the drawing, and cut and folded in a manner to form flaps hereinafter designated side flaps 12 and 13, and end flaps 14 and 15. By the initial folding operation it will be noted that the side flaps are separated, causing the end flaps to extend inwardly to overlap portions of the side flaps as shown in Figure 2.

70 As a result of the initial folding operation, the top plies 16 of the flaps 14 and 15 are a continuation of the underneath plies 17 of the side flaps 12 and 13.

75 The side flaps 12 and 13 are adapted to be folded inwardly, one upon the other, along the lines 18 and 19, and secured so as to complete the bag end, as shown in Figure 1, but in order to effect an inter-leaving, the flap designated 12 in Figure 2 is divided into two flaps 12 and 12', as shown in Figure 3, by first cutting as at 21 the folded edges between the top plies 16 and the underneath plies 17, as indicated by the bracket 20 in Figure 2.

80 In the present type of bag the cut 21 produces a flap 22, which is cut off as at 23 to expose a portion 24 of the next beneath ply of the underside of the end flaps.

85 With the flap 12 so cut as to produce the two flaps 12 and 12', the innermost flap 12 is folded inwardly first, as is shown in Figure 100

3, and secured to the upper ply of the end flaps 14 and 15.

The necessity for cutting the small triangular flap 22 away as at 23, is for the purpose of permitting the portion 24 of the next beneath ply which is uncut to come in contact with and be secured to the upper surface of the end flaps 14 and 15. With the parts so folded, adhesive is placed on the surfaces 25 of the flaps 12 and 12', which are then presented upwardly, after which the side flap 13 is folded inwardly, as shown in Figure 4 and secured to the upper surface of the flap 12. After this is accomplished, 10 the outside single ply flap is then folded inwardly on top of the then outer surface of the flap 13 to cover and conceal the entire joint and present a bottom as shown in Figure 1. It is obvious that the last ply, 15 being of a single thickness, readily adheres to the other parts, quickly dries, and forms a smooth, neat, strong, finished bottom for the bag.

In the above illustrated form, what would 25 ordinarily be two-side flaps have been formed into three flaps so as to present a single ply covering flap on the outside, but it is obvious that by arranging cuts similar to the cut 21 along the margins, either on one or both of 30 the flaps 12 and 13 that the multi-ply flap may be separated to form as many individual flaps of as many plies as desired, and that the flaps may be inter-leaved and glued one upon the other with a final finishing or covering flap 35 placed on top so as to produce the smooth outer surface shown in Figure 1.

For the purpose of separating the individual plies, the notch 30 is first provided for separating the opposite sides of the tube, one 40 from the other, for effecting the initial fold as shown in Figure 2. The purpose of the notch, is to permit fingers of folding mechanism to grip one of the multi-ply walls without carrying with it the opposite wall.

45 Likewise, wherever additional separation of plies is to be accomplished, as for instance between the flaps 12 and 12', additional cuts or notches 31 may be provided to permit machinery to grip or fold one flap without disturbing the other. It is obvious that instead of locating the notches 31 in the single 50 ply flap 12', it is possible to separate flaps 12 and 12' by notching the flap 12 when mechanism is employed constructed to accommodate such change. If this be the case, the 55 finishing or covering flap 12' will remain wholly intact in an unnotched condition. The notches will, of course, in any case be located for cooperation with the particular 60 machine employed.

When bottoms are being formed the ends 65 will be folded and secured as above described, but it is to be understood that when a valved end top is being made that one end of the bottom is left unsecured to provide an open-

ing for the introduction of a filling tube. This is accomplished, for instance, by leaving one end of the flap 12, as folded on the upper surface of the end flap 15, unsecured and likewise leaving the inner surface 32 of the flap 13, as shown in Figure 3, unsecured where it engages the upper portion of the end flap 15. Such an opening constitutes the well known type of valve opening for bags.

70 It is to be understood that the present invention is not to be limited to a bag provided with notches 31, as these are provided merely for the purpose of accommodating the multi-ply walls of the tube mechanism which will separate the various plies to form the independent flaps 12 and 12'.

75 It is obvious that other means may be provided for accommodating the construction to suitable mechanism, one particular alternative form of which is shown in Figures 9 to 11, inclusive, and will be hereinafter more fully pointed out.

80 In Figure 5 a modified form of bag is shown, in which the plurality of plies 50, 51, 52 and 53 are formed by cutting what would 85 otherwise be the multi-ply side flap. Likewise, by cutting, the other side flap is converted into a plurality of individual flaps 54, 55, 56 and 57. The row of notches 60 is provided so that the opposite side walls of 90 the tube constituting the bag may be separated to accomplish the initial folding and the smaller notches designated 61 and 62 are provided as one means for accommodating 95 the flap construction to mechanism for separating each individual ply from the remaining 100 ply. It is obvious from this showing that each ply may be inter-leaved with the plies of the opposite side flap and by considering this modification, together with the modification 105 shown in Figures 1 to 4, it will be further appreciated that any arrangement of inter-leaving may be effected and is contemplated 110 in this invention.

115 By referring to Figure 6 it will be noted that a modified form of notching is provided by making cut-outs 70, 71, 72 and 73 in one flap in successively larger arcs about the same center so that an edge of each strip is individually presented in a manner to be gripped 120 by properly adjusted gripping mechanism. The same type of notches are shown at 74 and 75 in the opposite side flap for separating the 125 individual component flaps.

130 By referring to Figures 7 to 11, inclusive, it will be noted that this modified form of the invention contemplates a slightly different type of cutting of the multi-wall tube prior to the initial folding operation, and is one which produces the straight edges 80 and 81 between the side and end flaps. This particular modification illustrates the form of end where the side flap 82 remains intact with its entire number of plies unseparated and the opposite side flap, by cutting its outside 135

ply as at 83, is formed into two independent flaps 84 and 85. It will be noted that by cutting in this particular manner the triangular end portions 86 on the opposite sides 5 of the flap 83 are cut away from and are free to be folded inwardly with the side flaps 83 and independently of the flap 85.

It may be noted to better understand the construction that the small triangular portions 86 before the cutting as at 83 were continuations of the outer flap 85. The manner of folding to form the finished end is substantially like the modified form shown in Figures 1 to 4, inclusive, and is clearly illustrated in Figures 9 to 11, inclusive. Figure 8 illustrates the initial folding operation and Figure 9 shows the next succeeding operation where the flap 84 is folded inwardly and secured by adhesive to the upper ply of 20 the end flaps. The construction in this instance is such that the flaps 84 and 85 may be readily separated by folding mechanism in that suitable fingers or other contact elements may engage the small triangular portions 25 86 and by proper movement cause the same to be folded inwardly without folding the outer flap 85 with it. The next folding operation is disclosed in Figure 10 where the side flap 82 is folded inwardly on top of flap 30 84 and properly secured. The finished end is accomplished by folding the flap 85 on top of flap 82 where it is secured to cover and protect the entire jointure between the flaps and provide a smooth, neat appearing finished end.

It will be readily appreciated that the particular manner of cutting illustrated in this form for providing the small triangular portions 86 eliminates the necessity for notching 40 either of the flaps 84 and 85 for effecting a separation thereof.

The advantages of this invention which are realized from the particular disclosure herein given, among others not enumerated, 45 are that a more secure, neater appearing bag end is provided, which is strong and durable in service. It is further one which may be more quickly produced in that it hastens the drying action of the adhesive. This is true 50 because the adhesive is applied to a larger absorbing surface than in bags of other constructions, and further in that a small volume of adhesive may be employed for securing comparatively thin flaps as compared 55 with bulky, multi-ply flaps.

As above brought out, although this invention is applicable to multi-ply tubes of the nested tube type, it has particular advantage as applied to the convolute type disclosed in 60 the co-pending application referred to for the reason that the tube end may be formed by initially cutting the elongated edge of the strip of stock before the tube is wound. This renders it quite easy to provide cuts in the 65 multi-ply tube which penetrate only a single

ply or a number of plies less than the entire thickness of the bag. It, of course, is understood that the cuts will be so made and located that the proper cut tube edge will be formed by registration by winding the tube. 70

The above disclosure is given merely as one embodiment of the present invention, which is not to be considered as limiting the invention in any way. The scope of the invention will be determined by an understanding of 75 the present disclosure as one embodiment thereof and will be particularly pointed out in the appended claims.

I claim:

1. A bag comprising a multi-ply tube having a bottom including portions of said tube, said bottom comprising side flaps, one of said side flaps constituting a plurality of flaps of less thickness than said tube, all of said side flaps being interleaved and secured one upon 85 the other.

2. A bag of the character described comprising a multi-ply tube, said tube having multi-ply opposed extensions constituting flaps, at least one of said flaps having some 90 of its plies separated to form a plurality of flaps, said flaps being folded inwardly and interleaved to form a bottom for said bag.

3. A bag of the character described comprising a multi-ply tube and a folded end, 95 said end comprising opposed flaps formed from portions of said tube, two of which are on the same side of said bag and of less thickness than said tube, all of said flaps being interleaved and secured to each other.

4. A bag of the character described comprising a multi-ply tube, said tube having multi-ply opposed extensions folded inwardly forming an end for said bag, one of 105 said extensions constituting a plurality of flaps interleaved with and secured to the opposed extension.

5. A bag of the character described comprising a multi-ply tube, a portion of said tube being folded to form opposed end and side flaps, one of said side flaps having some 110 of its plies separated to form flaps of diminished thickness, and all of said flaps being folded inwardly and interleaved and secured one upon the other.

6. A bag of the character described comprising a multi-ply tube, a portion of said tube being folded to form opposed end and side flaps, one of said side flaps having some 120 of its plies separated to form flaps of diminished thickness, and all of said flaps being folded inwardly and interleaved and secured one upon the other, said flaps having means permitting ready separation each from the 125 other.

7. A bag of the character described comprising a body portion and a bottom having opposed multi-ply flaps, the plies of said flaps constituting individual thinner flaps in- 130

terleaved and secured in overlapping relation.

8. A bag of the character described comprising a body portion and a closed end, the closed end including opposed multi-ply flaps, one of said flaps having its plies separated and having certain inner plies folded in beneath plies of the opposing flap and having its outer ply overlying the outer ply of the

10 opposed flap.

9. A bag of the character described comprising a body portion and a closed end, said end including opposed flaps, one of which flaps is multi-ply and has its plies separated

15 to form an inner part and an outer part with the inner part underlying the opposed flap and the outer part overlying the opposed flap.

10. A bag in accordance with claim 9 and
20 in which the outer part consists of one ply and the inner part of the remaining plies of the flap.

Signed at Fitchburg, Mass., this 5th day
of June, 1928.
